UNITED STATES PATENT OFFICE.

ERNEST M. ACH, OF CINCINNATI, OHIO, ASSIGNOR TO THE SAMUEL ACH COMPANY, OF CINCINNATI, OHIO, A CORPORATION OF OHIO.

LADY'S TRIMMED HAT.

Application filed August 13, 1925. Serial No. 50,059.

This invention relates to improvements in ladies' trimmed hats, particularly to a ready-to-wear product, adapting the same to be conveniently and quickly fitted or adjusted 5 to various head sizes without alteration to the outer coverings or lining or removal of the trimmings, and to the method of making the hat.

Under the prevailing fashion and style of 10 ladies' hair dressing it is desirable to have the hat fit close upon the head, special fitting of the hat to the head of the wearer being required for obtaining an appropriate setting. Trimmed hats generally represent 15 a suitably shaped crown form or frame of a sized buckram material, a covering which may include ornamental trimmings applied over the form or frame to cover the exterior and a lining covering the interior of the 20 form or frame.

These forms or frames are made in a very limited range of sizes, and which it would not be desirable or feasible to increase for 25 it would be of no avail to meet the conditions, as ladies' trimmed hats for each particular design are not merchandised to a dealer in different head size lots, the variation being particularly to style or design. Therefore alteration for head sizes usually 30 is required for each customer, calling for the services of a milliner, adding to the cost of the headwear, which is detrimental to merchandising ready-to-wear apparel.

The present improvement has for an object 35 the construction of ladies' trimmed hats complete in millinery and tailoring, having a split rim where the hat is provided with a rim and a split crown adapting the parts to be drawn together and overlapped or 40 adjusted to vary its band dimension and to size it to the head of the wearer.

Further objects and advantages of the invention will be more fully set forth in the description of the accompanying drawing 45 forming a part of the specification, in which:

Figure 1 is a perspective view of a lady's hat formed embodying my improvement.

Figure 2 is a perspective view of a trimmed and finished hat.

Figure 3 is a sectional view taken on line 3—3, Fig. 1, showing the cut-out portion of the crown and the flap.

Figure 4 is a cross section of a portion of

the crown frame at the cut-out side illustrating the covering and lining bordering 55 along the outline of the cut-out.

It is a general practice in the manufacture of some types of ladies' hats to employ a fabric form, or frame suitably shaped as a base over which covering and lining materials are applied. The form or frame is 60 preferably made of a sized buckram pressed into a desired crown configuration, either with or without rim and modeled for producing a particular fashion of hat. These 65 forms or frames are principally made from a single piece of material although not necessarily so, only its integrality is desirable as it admits more convenient blocking and gives permanency to its blocked form. These 70 forms or frames commercially are made to several sizes and ordinarily in the process of millinery are fitted to a particular head size as by the insertion of a bandeau and linings, a custom made job which is avoided 75 in the present invention.

Any of the commercial fabric hat forms may be employed, and referring to the drawings 1 indicates the crown of a hat form and 2 a suitably shaped fabric rim, which may 80 be of a separate piece of material stitched or otherwise secured to the base edge of the crown. The rim may be integral of the crown although in the separable form greater latitude is offered as various types 85 and forms of rim may be applied to a given shape of crown.

A portion of the crown at one side is cut out, or slotted, the drawings showing a cut-out of curved or semi-oval outline as indicated in dotted lines 3. A lap piece 4, preferably of a sized fabric is secured at one end to the crown to cover the cut-out portion and provide a flap and the means for adjustably securing the crown in a contracted condition. 90 The cut-out portion of the crown provides for considerable contraction of the crown at the base edge 5 without materially affecting the general shape of the crown. The outline of the crown cut-out and that of the flap 95 may be of various designs most adaptable for the particular design of hat. The flap as shown is partially bound with a binding tape 6 enclosing wire reinforcement to give it increased stiffness and edge thickness, and 100 the outer edges of the rim 2 may be simi- 105

larly bound. The rim 2 is of split form, with one end 7 extending beyond the crown cut-out, to provide for a suitable overlap of the ends thereof in the finished hat in 5 its normal hat size.

In a preferred method of making the hat, the crown is lined, and covered, without the flap. Likewise the exposed opposite side of the rim is covered, following the usual 10 methods employed in millinery, except that the lining and covering are brought to a border edge following the outline of the crown cut-out. The flap individually is suitably covered on both sides, the outer side 15 having a rosette 8 or other ornamental trimming. Such covered flap is then for a portion of its outline permanently secured to the extended rim portion 9 and covered crown, lapping over the crown side opening. 20 This permits the crown to be contracted to a desired hat size dimension after which the free end of the flap in its adjusted position is pinned, stitched or otherwise fastened to the crown to hold the parts secure. In merchandizing the hat one end of the flap is free 25 to permit making an immediate adjustment. The finished hat in display bears no effects of the adjustment features nor is it limited

to any particular style or design of hat, although it might be more adaptable in some 30 designs over others.

Having described my invention, I claim:

1. A lady's hat comprising a crown portion having an opening at one side, the opening being of semi-oval form extending from 35 the base line of the crown upwardly into the crown and a split rim adapting the crown to be retracted for adjusting the head band dimension thereof, the rim extending beyond said crown opening for overlapping the rim 40 ends in retracting the crown, and a flap covering said crown opening secured to the crown.

2. A lady's trimmed hat, comprising a crown frame having at one side a portion 45 thereof cut out, covering material applied over the crown, bordering along the outline of the cut-out, adapting the crown to be retracted, and an ornamental trimming applied over said cut-out portion of the crown 50 constituting a flap for securing the crown to an adjusted head band dimension.

In witness whereof, I hereunto subscribe my name.

ERNEST M. ACH.
